CLAIM

The ornamental design for a patio table planter, as shown and described.

DESCRIPTION

FIG. 1 is a perspective drawing showing front and top views of my new design for a patio table planter and wherein the matter shown in dashed line comprises no part of the invention;

FIG. 2 is a front view thereof and wherein the rear and right and left side views are identical;

FIG. 3 is a top view thereof; and,

FIG. 4 is a bottom view thereof.
